DENTAL FLOSS HOLDER

Guido R. Di Giuseppe, 2519 S. Sartain St.,
Philadelphia, Pa. 19148

Filed Jan. 2, 1968, Ser. No. 10,002

Term of patent 14 years

(Cl. D24—1)

FIG. 1 is a top perspective view of a dental floss holder, embodying my new design; the undisclosed bottom side is a mirror image of the top shown;

FIG. 2 is a top perspective view thereof, with the cover member in an open position;

FIG. 3 is a rear elevation thereof;

FIG. 4 is a side elevation thereof.

The dominant features of my design reside in the portions shown in full lines.

I claim:

The ornamental design for a dental floss holder, as shown and described.
